TURBINE DISK

Adrian Albert Lombard, Allestree, Frederick William Walton Morley, Aston-on-Trent, Christopher Ainsworth Davis, Barrow-on-Soak, near Loughborough, and Stanley Clarke Wilkinson, Colne, England, assignors to Rolls-Royce Limited, Derby, England, a British company

Original application October 2, 1947, Serial No. 777,506. Divided and this application December 19, 1950, Serial No. 201,644. In Great Britain October 2, 1946

3 Claims. (Cl. 253—39.15)

1

This application is divided out of our copending application Serial No. 777,506 filed October 2, 1947.

This invention relates to gas-turbines and more particularly to turbine-disc-assemblies of the kind in which the turbine-disc comprises two complementary parts spaced axially and supporting peripherally the turbine-blading therebetween. In such constructions it has been proposed to provide a space between two parts of the disc forming a passage for air cooling the disc and blades and/or their fixing.

In gas-turbine engines for aircraft-propulsion, to which the invention is particularly though not exclusively applicable, it has been the practice to manufacture turbine-discs from solid forgings, which in order to accommodate for high centrifugal loading and to avoid vibration or "whip," have been of relatively thick section. In addition, owing to the elevated temperature at the periphery of the disc it has been necessary to manufacture a disc from special high temperature steels. Such turbine-discs have been cooled by applying air on one face and deflecting the air at the outer periphery of the disc to cool the blade root fixings; in practice, however, such cooling has been relatively ineffective.

The object of the present invention is to provide a turbine-disc and blade-construction which will facilitate manufacture, and improve the blade or blade-root cooling efficiency.

The nature of the invention will be appreciated by reference to the following description of a preferred embodiment illustrated in the accompanying drawings, in which:

Figure 1 is a local radial section through a turbine disc,

Figure 2 is a partial end view of Figure 1 with parts broken away.

Referring to Figures 1 and 2, there is illustrated an axial flow turbine assembly comprising two slightly dished disc parts with the turbine blading mounted in a blade-supporting ring received between the peripheral portions of the discs.

The two disc parts 10, 11 are generally similar to one another, decrease in thickness from their centres towards their peripheries to economise in material and are assembled with the concave faces together. The disc material may be a high tensile steel, such as that known under the trademark "Hykro," having the desired properties at the moderate temperature at which it runs.

The disc part 10 is provided with a mounting flange 12 at its outer side by means of which the disc can be secured to a turbine-rotor shaft.

2

Each disc is formed with an internal axial flange 13 at about the same radius as the mounting flange 12, and the flanges 13 abut one another to space the two disc parts 10, 11 the correct distance apart at their centres. One of the flanges is arranged to fit, in the manner of a spigot, within the other so as to resist centrifugal and gyroscopic forces, and thermal loading tending to cause relative radial displacement between the disc-parts.

Each disc part is formed with a central hole to receive a sleeve 14 and the two disc parts are clamped together at their centres between a flange 15 on the sleeve 14 and a nut 16 on the sleeve. The sleeve 14 is open at one end to the shaft and is closed at the other so that cooling air can pass from the shaft into the sleeve and then through openings 17 in the sleeve 14 and flanges 13 into the turbine disc.

Each disc part 10, 11 is formed with an internal shoulder 18 near its periphery and these shoulders face radially inwards so as to form sockets of large diameter. Immediately outside the shoulder 18 the disc parts are formed with two sets of annular facings 19 between which the blade supporting ring 20 is located. The material of this ring may be that known as G.18.b (manufacturer's specification or trade-mark), having the desired properties at the elevated temperature to which the ring is subjected. The ring 20 is formed with two outwardly facing shoulders 21 which constitute large diameter spigots fitting in the sockets formed by the shoulders 18. The disc parts are secured towards their peripheries against moving apart axially by counter-sunk bolts 22 which are arranged in a circle along the centre-line of the facings 19 and are thus in a portion of the disc which is subject to a considerably reduced centrifugal loading, the centrifugal loading due to the blades 23 and blade supporting ring 20 being applied to the disc through the engaging shoulders 18, 21.

The peripheral portions of the disc parts 10, 11 beyond the facings 19 are shaped to provide between them a wide trough 24 and the blade-supporting ring 20 extends radially outwards beyond the trough, the part of the ring 20 beyond the trough 24 being widened to close the trough. There is, however, a space inside the trough on either side of the blade-supporting ring 20.

The facings 19 are formed with a plurality of radial slots 25 extending across them and also with arcuate slots 26 joining pairs of slots 25. The shoulders 21 on the ring 20 are also formed with radial slots 27 to register with the slots 25.

The cooling air can thus pass into the trough 24 through the passages provided by these slots and will adequately cool the periphery of the disc parts 10, 11 and the inner part of the blade-supporting ring 20.

The peripheral part of the ring 20 is formed with shaped recesses 29 to receive and retain the roots 28 of the blades 23, the roots being conveniently provided with peripherally extending shoulders so that they are of the "fir-tree" type which are mounted in the blade-carrying ring by being slid into it in an axial direction. Slots 30 are cut across the bottom of the recesses 29 so that cooling air can escape from one side of the trough 24 underneath the roots 28 of the blades. In certain cases the blades 23 may be hollow and part of the air will then pass up through the blades to cool them. Passages 31 are formed in the portions of the ring 20 between the blade roots 28 to permit the escape of cooling air from the trough 24 and to assist in cooling the blade roots.

Each of the disc parts 10, 11 is provided with an axial flange 32 on its inner surface at a short distance inwards from the blade supporting ring 20 and these flanges abut one another when the discs are assembled. Slots 33 are formed in the flanges 32 to register and form passages for the outward flow of cooling air. The flanges 32 inter-abut to determine the spacing of the discs 10 and 11 independently of the blade-root fixing they are between, and thus avoid compressive stresses in the latter, whilst additionally, axial clearance between the faces of the root-fixing and the disc-parts may provide for the passage of cooling air.

Each disc part is also formed with an internal axial flange 34 at a distance from the centre equal to about half the disc radius and these flanges 34 provide inwardly facing shoulders 35 forming sockets to receive a ring 36 which acts as a spigot in each of them. The ring 36 is preferably formed from a material, having a high coefficient of expansion, such as aluminium, so that it will tend to tighten in the sockets as the temperature rises. The ring 36 is formed with slot 37 on each of its side faces to provide passages through which cooling air can pass outwards and each slot 37 is made deeper at its outer end in order to clear the flanges 34. This arrangement has the result that the air will tend to flow outwardly along the inner faces of the discs 10, 11 to the slots 37 and will escape from these slots towards the central plane of the turbine-disc-assembly so that the two streams of air flowing on the opposite sides of the ring 36 will be directed towards the central plane of the turbine-disc and towards one another to produce turbulence. This turbulence reduces the tendency for a stratified air flow in which the air flowing over the parts of the disc will be hotter than that flowing up the central plane of the disc.

The spigot-like couplings between the blade-supporting ring 20 and each of the disc parts 10, 11, between the ring 36 and the disc parts 10, 11, and between the axial flanges 34 serve to resist centrifugal, gyroscopic or thermal loading which tend to make the disc parts move relatively to one another in a radial direction.

The clamp device at the centre of the turbine disc assembly provided by sleeve 14, flanges 15 and nut 16, avoids the use of a series of bolts passing through the disc parts, and localizes the bore through the centre of the disc, thereby avoiding undue reduction in structural strength. Like-

wise, it will be appreciated that the provision of the flange 12 avoids the passage of bolts through the disc-parts in their attachment to the turbine shaft.

5 The disc parts 10, 11 being coned will tend to separate under centrifugal force at full speed. The bolts 22 are tightened up so that the axial load between the flanges on the disc parts and between the disc parts and the ring 36 are greater than the maximum force tending to separate the disc parts when running at maximum speed.

It will be appreciated that the construction of turbine disc above described is light in weight and yet is capable of withstanding the high 15 stresses experienced when in use, is relatively simple to manufacture, and, by virtue of the method of blade-root fixing, has an improved cooling efficiency as regards the blade-root cooling.

20 Moreover, by locating the screws, bolts or rivets for securing the disc together outside the region of the part of their peripheries subjected to high centrifugal stresses, the discs are not unduly weakened by the provision of the holes to receive 25 the bolts, screws or rivets.

Furthermore, the construction of turbine disc of this invention enables the various parts of the disc to be manufactured from a material having the desired strength properties at the temperature at which it will operate. Thus the dished 30 discs may be formed from a material having desired strength properties at a temperature which is moderate as compared with that at which the blading or the blade-supporting ring will 35 operate and the blading or blade-supporting ring will be made from a material having desired strength properties at a more elevated temperature.

We claim:

1. An axial flow turbine assembly, comprising in combination a first disc part having means for securing it to a hollow rotor shaft; a second disc part mounted coaxially with the first and axially spaced therefrom to provide a hollow space therebetween; a duct leading to said space for the supply of cooling gas; shoulder means on said disc parts adjacent the peripheries thereof and extending axially towards one another; an annular blade supporting ring mounted in said space and provided with axially extending circumferential spigot means abutting the radially inward faces of said axially extending shoulder means on said disc parts; axial flow turbine blading supported by said blade supporting ring; securing members to secure said disc parts against axial separation extending through the disc parts, and through said ring and located at a radius outside said spigot means; and passages in said axially extending shoulder means and said axially extending circumferential spigot means communicating between said space and the exterior of the disc assembly to permit the flow of cooling gas from said space, such flow cooling the ring and peripheral portions of the discs by direct contact therewith.

2. An axial flow turbine assembly, comprising in combination two complementary disc parts secured to each other and axially spaced to provide a hollow space therebetween; means for supplying cooling gas to said space; axial abutment means on said disc parts defining said axial spacing at an inner radius; shoulder means on said disc parts at a radius outside said abutment means and extending axially towards one another; an annular blade supporting ring provided

with axially extending circumferential spigot means abutting the radial inward faces of said axially extending shoulder means; axial flow turbine blading supported by said blade supporting ring; securing members to secure said discs against axial separation extending through said disc parts and through said ring and located at a radius outside said spigot means; circumferential shoulder means on said disc parts extending axially towards each other into said space and located at radius between said first mentioned shoulder means and said abutment means defining the axial spacing of the disc parts at inner radius; a spacer ring in said space engaged in axial abutment by said disc parts and dimensioned to engage in radial outward abutment with said circumferential shoulders; passages formed in said ring to permit passage of cooling gas radially outward through said ring; and passages in said first mentioned shoulder means and said axially extending circumferential spigot means communicating between said space and the exterior of the assembly to permit the flow of cooling gas from said space, such flow cooling the ring and peripheral portions of the discs by direct contact therewith.

3. An axial flow turbine disc assembly, comprising in combination a first disc part; a second disc part mounted coaxially with said first disc part, said first and second disc parts having coaxial bores; a hollow bolt member extending through said bores; a nut member engaged on said bolt member; spacing means axially nipped between said discs by said bolt and nut members and holding said discs apart to provide a hollow space therebetween radially outside said spacing means; a communicating duct from said coaxial bores to said space, said communicating duct

passing through said bolt; shoulder means on said disc parts adjacent the peripheries thereof and extending axially towards one another; an annular blade supporting ring provided with 5 axially extending circumferential spigot means abutting radially inward faces of said axially extending shoulder means on said disc parts; axial flow turbine blading supported by said blade supporting ring; securing members to secure said disc parts against axial separation extending through said disc parts and through said ring and located at a radius outside said spigot means; and passages in said axially extending shoulder means and said axially extending circumferential spigot means communicating between said space and the exterior of the disc assembly to permit the flow of cooling gas from said space, such flow cooling the ring and peripheral portions of the discs by direct contact therewith.
